INVENTOR

UNITED STATES PATENT OFFICE.

CHRISTOPHER C. BATCHELOR, OF BALTIMORE, MARYLAND, ASSIGNOR TO C. B. SEAL COMPANY, A CORPORATION OF MARYLAND.

FASTENING AND SEALING DEVICE FOR PAILS.

No. 922,557.

Specification of Letters Patent.

Patented May 25, 1909.

Application filed December 26, 1907. Serial No. 408,071.

To all whom it may concern:

Be it known that I, CHRISTOPHER C. BATCHELOR, a citizen of the United States, residing at Baltimore, in the county of Baltimore and State of Maryland, have invented certain new and useful Improvements in Fastening and Sealing Devices for Pails, of which the following is a specification.

My invention relates to devices for fastening the tops on buckets or pails used for shipping merchandise such as confectionery, bakery products, etc., and has for its object the provision of a fastening device that is reasonable in cost of manufacture and expense of application and that will effectually engage the cover so as to prevent pilfering from the package in transit.

My invention will be described in detail hereinafter and illustrated in the accompanying drawings in which—

Figure 1 is a view in perspective of a pail having my improved fastening and sealing device in position thereon, Fig. 2, a fragmental sectional view showing the means for fastening the ends of the straps to the pail, Fig. 3, a detail view showing the preferred means for fastening the meeting ends of the fastening straps together, and Figs. 4 and 5, views showing modified forms of means for sealing the ends of the straps.

In the drawings similar reference characters indicate corresponding parts throughout the several views.

1 indicates a bucket or pail made of wood, paper pulp or other suitable material having the hoops 2 and cover 3. Heretofore in shipping merchandise in packages of the form shown there has been great annoyance caused by the pilfering of the contents of the packages which in the case of sweetmeats, cakes and similar goods has proved a great temptation to idle men and boys. Several fasteners have been used to prevent access to the contents of the pail but they have been either too expensive to be practicable or ineffective in accomplishing the purpose intended.

My invention contemplates the provision of a practical means for sealing the cover in place and that is so reasonable in cost of manufacture and installation that the addition to the cost of the package is infinitesimal.

My invention consists of a number of straps of metal 4 each of which has one end inserted under one of the hoops 2 on the

bucket, preferably the bottom one, and secured by a nail or other driven fastening 5 driven through the hoop and end of the strap. The straps are then bent upwardly so as to cover the head of the nails 5 and extended over the edge of the cover and joined together in the approximate center of the cover.

The preferred means as shown in Fig. 3 of the accompanying drawings for joining the ends of the straps consist of a rivet 6 but any other means may be substituted therefor such as soldering the ends together as shown in Fig. 4 or joining the ends together by means of a strand of wire and sealing the ends of the wire together as shown in Fig. 5 if desired, the principal feature of my invention being the manner of securing one of the ends of the straps under the hoop and the other ends together in the center of the cover 75 so as to prevent removal of the cover without breaking the fastening in the center and disclosing the fact that the package had been broken. For further security in fastening the ends of the straps together the end of the rivet in Fig. 3 after being clenched, or the solder in Fig. 4, as well as the seal shown in Fig. 5 are impressed with any distinctive mark such as the initial of the shipper or an arbitrary emblem so that the consignee can tell before opening the package whether or not it had been tampered with.

Having thus described my invention what I claim is—

1. In combination with a pail having hoops thereon, and a cover on the pail, straps having one of their ends inserted upwardly under one of the hoops, a driven fastening secured through the hoop and strap end, the other ends of the straps secured together over the approximate center of the cover.

2. In combination with a pail having hoops thereon, and a cover on the pail, straps having one of their ends inserted upwardly under one of the hoops, a driven fastening secured through the hoop and strap end, the straps then bent upwardly over the side of the pail so as to cover the exposed end of the driven fastening, and the free ends of the straps extended over the cover and having their ends riveted and sealed together in the approximate center of the cover.

3. In combination with a pail having hoops thereon, and a cover on the pail,

straps having one of their ends inserted upwardly under one of the hoops, and secured thereto, the straps then bent upwardly over the side of the pail and extended over the cover, and the free ends of the straps secured together in the approximate center of the cover.

4. In combination with a pail having hoops, and a cover, straps having one of their ends inserted upwardly under one of the

hoops, then bent upwardly over said hoop, the sides of the pail, and the cover, and their ends secured together in the approximate center of the cover.

In testimony whereof I hereto affix my 15
signature in the presence of two witnesses.

CHRISTOPHER C. BATCHELOR.
